CONTAINER

Edward D. Gillam, Philadelphia, Pa.

Application August 26, 1942, Serial No. 456,193

7 Claims. (Cl. 206—44)

This invention relates to improvements in containers and more particularly to display containers of the type in which merchandise is in view and accessible for sale.

It is the principal object of the present invention to provide a display container which may be readily filled, easily assembled and closed, and quickly opened for display, and which is particularly suited for handling at any stage by unskilled labor.

It is a further object of the present invention to provide a display container into which the contents may be readily introduced.

It is a further object of the present invention to provide a display container which may be readily assembled and closed in compact condition with adequate protection of the contents.

It is a further object of the present invention to provide a container which may be readily set up for the display of the contents.

It is a further object of the present invention to provide a display container having a high degree of rigidity and which is supported in an advantageous manner.

Other objects of the invention will be apparent from the annexed specification and claims.

The nature and characteristic features of the invention will be more readily understood from the following description, taken in connection with the accompanying drawings forming part hereof, in which:

Fig. 1 is a view in perspective showing a container embodying the main features of the present invention set up in display condition;

Fig. 2 is a view in perspective showing the container in closed condition;

Fig. 3 is a central longitudinal sectional view showing the container set up in display condition;

Fig. 4 is a central longitudinal sectional view showing the container in closed condition and ready for shipping;

Fig. 5 is a fragmentary rear elevational view showing certain details of the corner construction and the support of one of the rear corners of the box of the container;

Fig. 6 is a bottom view of one of the rear corners of the box of the container showing the slot;

Fig. 7 is a plan view of one of the blanks employed in connection with the container of the present invention and which when folded supplies a cover for the container and also a support for the container; and

Fig. 8 is a plan view of another blank employed for making the box portion of the container.

It will, of course, be understood that the description and drawings herein are illustrative merely, and that various modifications and changes may be made in the structure disclosed without departing from the spirit of the invention.

Referring more particularly to the drawings, in Fig. 7 there is shown the blank 10 which provides a cover and a support, this blank 10 preferably being formed from suitable paperboard or the like, and finished on one face thereof for printing if desired.

The blank 10 preferably includes a terminal flap 11 joined to a longitudinal or base forming panel 12 along a transverse crease line 13. A tongue 14, swingable at the crease line 13 is preferably cut in the terminal flap 11 for purposes hereinafter explained. A support panel or leg portion 15 is joined to the longitudinal panel 12 along a transverse crease line 16, the support panel 15 having outwardly extending projecting portions or wings 17 which extend beyond the remaining portions of the side edges of the blank 10. A container engaging panel 18 is joined to the support panel 15 along a transverse crease line 19. A display panel 20, which is adapted to receive printed advertising matter or the like, is joined to the container panel 18 along a transverse crease line 21.

Fig. 8 shows the blank 25 which is preferably made of the same material as the blank shown in Fig. 7 and includes a central panel 26 which is adapted to form the bottom wall or floor of the container. The central panel 26 has rectangular side wall panels 27 joined thereto along longitudinal crease lines 28. An outside front end wall panel 29 is joined to the central panel 26 along a transverse crease line 30, a slit 31 being cut along the crease line 30 for the reception of the tongue

32, as hereinafter more fully pointed out. Front end wall flaps 32 are joined to each of the side wall panels 27 along transverse crease lines 33 which are formed as extensions of the crease line 30. The front end wall flaps 32 have portions removed therefrom as at 34 for clearance as will hereinafter appear.

Each of the side wall panels 27 has a rear wall flap 35 joined thereto along aligned transverse crease lines 36. An inner flap portion 37 is connected to the central panel 26 along a transverse crease line 38, the crease line 38 being offset inwardly from the crease lines 36 to provide a slot 40 for the insertion of the display panel 20 and the container engaging panel 18 as herein-after pointed out. The side edges 39 of the inner

flap portion 37 are preferably shaped so that the flap 37 does not bind against the inner faces of the side walls 27 when assembled.

The blank shown in Fig. 8 is assembled, preferably on a suitable box making machine. This is accomplished by bending the side walls 27 along the crease lines 28 to positions at right angles to the bottom panel portion 26, bending the front flaps 32 along the crease lines 33 and bending the outer front end panel 29 along the crease line 30 and gluing the end flaps 32 and the front end panel 29, with the front end panel 29 outermost. At the same time the inner flap 37 is bent along the crease line 38, the end wall panels 35 are bent along the crease lines 36 and the end wall panels 35 are secured to each other, preferably by gluing.

If it is desired to have a finished surface showing at the inside of the upper rear end of the box, this may be accomplished by turning a portion of the flap 37 back on itself as illustrated in dotted lines in Fig. 3. The turned down portion 37a of the flap 37 will then have an exposed finished surface and the exposed part of the container engaging panel 18 also has a finished surface.

It will be noted that a rigid box is thus provided and that the front wall consisting of the front wall flaps 32 and the front wall panel 29 will be capable of sustaining a relatively heavy load without deformation. It is not essential, however, that the specific form of box illustrated be employed, so long as the box has sufficient rigidity and is provided with a slot as at 40, or other suitable provisions for engagement by the support 15. The bottom wall or panel 26 also is preferably stiffened by the provision of the flap 37, and by reason of the stiffening there will be no tendency of the bottom wall to sag intermediate the side walls and adjacent the rear end walls when the box is filled. The arrangement of the flap 37 with respect to the slot 40 and the spacing thereof from the rear wall panels 35 facilitate the insertion of the support.

The blank 10 shown in Fig. 7 is inserted in the slot 40 and between the flap 37 and the end wall panel 35 with the finished face forward. This is effected by introducing the display panel portion 20 into the slot 40 from below and sliding the blank 10 upwardly to a position where the projecting portions 11 engage the bottom 26 of the box beyond the ends of the slot 40.

When it is desired to close the container for shipping the display panel portion 20 is bent forwardly along the crease line 21 to extend over the open top of the box. The blank 10 is bent first along the crease line 19 to position the support panel 15 contiguous to the outer face of the rear end wall 35 and base panel portion 12 is then bent forwardly so as to overlie the display panel 20. The terminal flap 11 is bent along the crease line 13 and inserted inside the lower end wall 32 of the box to the position shown in Fig. 4.

The box and its contents are then ready to be shipped, the contents being well protected by the display panel 20 and the panel portion 12. When it is desired to use the display container the panel portion 12 is elevated and the panel portions 12 and 15 are swung around the axis provided by the crease lines 19 and 16. The panel portion 12 is bent with respect to the support panel 15 along the crease line 16 and the tongue 14 is bent upwardly and inserted within the slit 31 as shown

in Fig. 3. The display panel 20 may then be bent backwardly to the desired angle to advantageously advertise the contents of the container.

It will be noted that the rigidity of the box aids in maintaining the attractive condition of the contents whether the same is wholly or partially filled and that the provision of the slot 40 and the flap 37 permit of the insertion of the supporting and covering structure after the box has been filled. The manipulation required to place the container in the desired condition for shipping or for display, as required, is very simple and obvious to the user.

I claim:

1. A container including a box having a bottom wall, side walls, and front and rear end walls, said rear end wall consisting of end flaps folded along upwardly extending crease lines disposed in a plane normal to the bottom wall and secured together, said bottom wall having a transversely extending slot at the rear end thereof, the forward margin of said slot being spaced forwardly from the plane of said crease lines, and a separable support for said box having a portion extending through said slot.

2. A container including a box having a bottom wall, side walls, and front and rear end walls, said rear end wall consisting of end flaps folded along upwardly extending crease lines disposed in a plane normal to the bottom wall and secured together, a rear flap extending upwardly from said bottom wall along a crease line spaced forwardly from said plane to provide a transversely extending slot, and a separable support for said box having a portion extending through said slot.

3. A container including a box having a bottom wall, side walls, and front and rear end walls, said rear end wall consisting of end flaps folded along upwardly extending crease lines disposed in a plane normal to the bottom wall and secured together, a rear flap extending upwardly from said bottom wall along a crease line spaced forwardly from the plane of said crease lines to provide a transversely extending slot, the edges of said flap being spaced inwardly from said side walls, and a separable support for said box having a portion extending through said slot.

4. A container including a box of folded sheet material having a bottom wall and front and rear end walls, said rear wall being provided with a vertical open ended passageway extending the width of the box, and a separable cover and support section for said box, said section being formed from flat sheet material and having a box engaging panel slidably into position in said passageway for holding the rear end of the box in elevated position, a leg panel of a single thickness of material providing a leg for sustaining the weight of the box, said leg panel having thereon a supporting projection in engagement with the under side of said box and limiting the upward movement of said leg panel, said leg panel being connected to said box engaging panel along a transverse crease line, a display panel extending upwardly from the box engaging panel and connected thereto along a transverse crease line, a base portion joined to said leg panel along a transverse crease line and extending forwardly to the front end of the box, and interengaging means on the front end of the base portion and on the bottom of the box for holding the bottom of the box and the base portion in fixed angular relationship, said leg panel and said base portion being of a combined length to cover the rear and

the top of the box and swingable to covering position.

5. A container including a box of folded sheet material having a bottom wall and front and rear end walls, said rear wall being provided with a vertical open ended passageway extending the width of the box, and a separable cover and support section for said box, said section being formed from flat sheet material and having a box engaging panel portion slidable into position in said passageway for holding the rear end of the box in elevated position, a leg panel of a single thickness of material providing a leg for sustaining the weight of the box, said leg panel having on opposite edges thereof marginal supporting projections extending sidewise beyond the ends of said passageway in engagement with the underside of said box and limiting the upward movement of said leg panel, said leg panel being connected to said box engaging panel along a transverse crease line, a display panel extending upwardly from the box engaging panel and connected thereto along a transverse crease line, a base portion joined to said leg along a transverse crease line and extending forwardly to the front end of the box, and interengaging means on the front end of the base portion and on the bottom of the box for holding the bottom of the box and the base portion in fixed angular relationship, said leg panel and said base portion being of a combined length to cover the rear and the top of the box and swingable to covering position.

6. A container including a box of folded sheet material having a bottom wall and front and rear end walls, said rear wall being provided with a vertical open ended passageway extending the width of the box, and a separable cover and support section for said box, said section being formed from flat sheet material with parallel side edges and having a box engaging panel slidable into position in said passageway for holding the rear end of the box in elevated position, a leg panel of a single thickness of material providing a leg for sustaining the weight of the box, said leg panel having thereon marginal supporting projections extending sidewise beyond said side edges in engagement with the underside of

said box beyond the ends of said passageway and limiting the upward movement of said leg panel, said leg panel being connected to said box engaging panel along a transverse crease line, a display panel extending upwardly from the box engaging panel and connected thereto along a transverse crease line, a base portion joined to said leg along a transverse crease line and extending forwardly to the front end of the box, and interengaging means on the front end of the base portion and on the bottom of the box for holding the bottom of the box and the base portion in fixed angular relationship, said leg panel and said base portion being of a combined length to cover the rear and the top of the box and swingable to covering position.

7. A container including a box of folded sheet material having a bottom wall and front and rear end walls, said rear wall being provided with a vertical open ended passageway extending the width of the box, and a separable cover and support section for said box, said section being formed from flat sheet material and having a box engaging panel slidable into position in said passageway for holding the rear end of the box in elevated position, a leg panel of a single thickness of material providing a leg for sustaining the weight of the box, said leg having thereon a supporting projection in engagement with the underside of said box and limiting the upward movement of said leg panel, said leg panel being connected to said box engaging panel along a transverse crease line, a display panel extending upwardly from the box engaging panel and connected thereto along a transverse crease line, a base portion joined to said leg along a transverse crease line and extending forwardly to the front end of the box, and a tongue on the front end of the base portion for engagement with a slot at the lower part of the box at the front for holding the bottom of the box and the base portion in fixed angular relationship, said leg panel and said base portion being of a combined length to cover the rear and the top of the box and swingable to covering position.

EDWARD D. GILLAM.
